CLAIM

The ornamental design for a component of playground slide, as shown and described.

DESCRIPTION

FIG. 1 is a top plan view of the ornamental design for a component of a playground slide;

FIG. 2 is a bottom plan view of the playground slide component;

FIG. 3 is a front elevational view of the playground slide component;

FIG. 4 is a rear elevational view of the playground slide component; and,

FIG. 5 is a side elevational view of the playground slide component as viewed from the left side thereof, the right side being symmetrically identical.
